UNITED STATES PATENT OFFICE.

PAUL R. VOGEL, OF CHICAGO, ILLINOIS.

FILING-CABINET.

1,332,087.

Specification of Letters Patent. Patented Feb. 24, 1920.

Application filed September 18, 1919. Serial No. 324,302.

To all whom it may concern:

Be it known that I, PAUL R. VOGEL, a citizen of the United States, residing at Chicago, in the county of Cook and State 5 of Illinois, have invented certain new and useful Improvements in Filing-Cabinets, of which the following is a specification.

My invention relates to filing cabinets and has for its primary object the provision of 10 an improved cabinet for the filing of cards, circulars, pamphlets, periodicals and similar matter, wherein certain partition members are, in a novel way, removably held in position by such means as readily admits 15 of their adjustment to vary the size of the filing spaces in the cabinet. Another object lies in the provision of means whereby cards or other articles to be filed may be held to view in a substantially vertical filing case 20 with the tops of the cards filed positioned nearer the observer than the bottoms of the cards, this object contemplating the retention of cards held in such position without obstruction to their removal from or in 25 sertion in the case and without the necessity for bending them in handling.

Other objects and advantages of the invention will appear from the following description, taken in conjunction with the accompanying drawings which form a part of this specification and illustrate the preferred embodiment of the invention.

In the drawings:

Figure 1 is a perspective view of the present invention taken at a point in front of same and slightly to the right thereof;

Fig. 2 is a fragmentary section taken approximately on line 2—2 of Fig. 1;

Fig. 3 is a side elevation of one of the improved partition members of this invention;

Fig. 4 is a fragmentary vertical section taken on line 4—4 of Fig. 1;

Reference numeral 10 indicates generally 45 a filing box comprising sides 11 and 12, a front wall 13 and an inclined flat panel 14. Positioned within the box 10 and extending from the bottom to the top thereof is a series of card supporting shelves numbered from 15 to 21 respectively. These shelves are elongated horizontally and slanted upwardly from the front to the back of the box, the forward edge of each shelf resting directly on the panel 14 and the 55 rear edge being supported considerably above the panel by means of a riser 22. In

cross-section as viewed in Fig. 2, the shelves 15—21 and their risers 22 form a serrated contour.

In order to divide the shelf space provided as above described, I employ any desirable number of partitions 23, the upper edge of each partition being preferably straight, and the lower edge mutilated to conform to the serrated contour presented 60 by the shelves and risers. The lower edge of each partition 23, therefore, comprises a succession of downwardly projecting teeth 24. As a means of securing each partition 23 in the desired location in box 10, I provide certain of the teeth 24 with a forwardly and downwardly projecting tenon 25 so positioned and pitched and of such size as to fit within a mortise 26 formed in the riser 22, or, as illustrated, in the front wall 13 of 70 the box 10. Preferably I provide two tenons 25 for each partition, positioning them on the first and last teeth of the partition. Horizontal rows of opposite mortises 26 are provided in the front plate 13 and in the 75 rear riser 22, these mortises being equally spaced from each other in the rows. The partitions are inserted by placing them upon the shelves of the filing cabinet and sliding them directly toward the front of the box, 80 this action being made possible by the fact that all of the shelves 15 to 21 inclusive are uniformly slanted. The insertion of the partitions 23 divides the series of shelves so that filing spaces 27 are formed horizontally 85 alined and vertically alined. Should it be desired to vary the horizontal extent of any of the filing spaces 27, one of the partitions 23 is removed by sliding it backwardly and is inserted in another opposite 90 pair of mortises 26. Doors 28, may, if desired, be provided for covering the filing cabinet.

This invention also contemplates the provision of an upstanding filing case generally indicated at 29 and comprising a base 31, side walls 32 and 33 and spaced superposed horizontal shelves 34. Slanting forwardly and upwardly from the rear edge of one shelf 34 to the forward edge of the 100 next superposed shelf is a back panel 35. The horizontally extending spaces partially defined by the shelves 34 and the backs 35 are divided into horizontal tiers of filing spaces 36 by means of division plates 37 105 which are positioned each in a vertical plane and have their forward edges slanting in

parallelism with the backs 35. Obviously, were cards to be inserted in the spaces 36, they would fall forwardly and out of the case 29 unless provision were made to secure them therein. It is plain also, that were a continuous board or panel positioned across the entire horizontal tier of spaces 36, that board would render invisible the greater portion of the cards or other matter to be filed. I therefore provide a small flat piece 38 glued or otherwise held against the lower portion of the forward edge of each division plate 37, the piece 38 extending from the forward edge of one shelf 34 only a part 15 of the distance upwardly to the next superposed shelf. Each piece 38 is positioned at right angles to the plane of its division plate 37, and is of sufficient horizontal extent to project beyond the opposite 20 sides of the division plate. Cards to be filed are therefore held against pitching forwardly from the case 29, while at the same time any reading matter or pictures printed on them will be exposed to the view almost 25 in its entirety.

While I have illustrated and described the preferred embodiment of the invention, it will be obvious that one skilled in the art may make modifications thereon without departing from the spirit of the invention. I wish, therefore, not to be restricted to the precise embodiment shown except in so far as the same is limited in the appended 30 claims.

35 I claim:

1. In a filing cabinet, the combination with a plurality of parallel shelves uniformly pitched and risers connecting the rear edge of each shelf with the forward 40 edge of the next, there being opposite mortises formed in a plurality of said risers, of a partition extending across said shelves comprising teeth depending into the spaces between the shelves, and a tenon for each of 45 said mortises formed on that tooth of the partition positioned opposite said mortise.
2. In a filing cabinet, the combination with a series of shelves defining parallel spaced planes, of a partition extending 50 across said shelves and comprising teeth

adapted to enter the spaces between said shelves, a riser supporting the rear edge of one of said shelves and formed with a mortise, and a tenon fixed upon said partition and fitting within the mortise. 55

3. In a filing cabinet, the combination with a series of shelves defining parallel spaced planes, of a partition extending across said shelves and comprising teeth adapted to enter the spaces between said 60 shelves, a riser supporting the rear edge of one of said shelves and formed with a mortise, and a tenon fixed upon said partition and fitting within the mortise, said tenon having its upper and lower edges paralleling 65 the planes of said shelves.

4. In a filing cabinet, the combination with a box and horizontally extending shelves positioned therein and uniformly slanted, of risers spacing the rear edge of 70 each shelf above the forward edge of the next shelf behind, opposite mortises formed one in the front wall of said box and the other in one of said risers, a vertical partition crossing said shelves from front to rear 75 of the box and mutilated in its lower edge to form teeth fitting the interstices between said shelves and risers, and tenons formed on each tooth and engaging said mortises.

5. In a filing cabinet, the combination 80 with a box and horizontally extending shelves positioned therein and uniformly slanted, of risers spacing the rear edge of each shelf above the forward edge of the next shelf behind, opposite mortises formed 85 one in the front wall of said box and the other in one of said risers, a vertical partition crossing said shelves from front to rear of the box and mutilated in its lower edge 90 to form teeth fitting the interstices between said shelves and risers, and tenons formed on each tooth and engaging said mortises, there being horizontally disposed rows of 95 mortises formed in said front wall and risers respectively whereby said partition may be shifted in position left or right within the box.

In testimony whereof I have affixed my signature.

PAUL R. VOGEL.
